US0D1059831S

(12) **United States Design Patent** (10) **Patent No.:** **US D1,059,831 S**
(45) **Date of Patent:** ** *Feb. 4, 2025

(54) **CASE FOR ELECTRONIC DEVICE**

(71) Applicant: **SPIGEN KOREA CO., LTD.**, Seoul (KR)

(72) Inventor: **Junyong Youn**, Seoul (KR)

(73) Assignee: **SPIGEN KOREA CO., LTD.**, Seoul (KR)

(*) Notice: This patent is subject to a terminal disclaimer.

(**) Term: **15 Years**

(21) Appl. No.: **29/790,652**

(22) Filed: **Dec. 7, 2021**

(51) LOC (15) Cl. **03-01**

(52) U.S. Cl.

USPC **D3/294**

(58) **Field of Classification Search**

(57) **CLAIM**

The ornamental design for a case for electronic device as shown and described.

DESCRIPTION

FIG. 1 is a front perspective view of a case for electronic device showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another front perspective view of the case for electronic device shown in an open state.

The portions shown in broken lines form no part of the claimed design.

1 Claim, 8 Drawing Sheets
